UNITED STATES PATENT OFFICE.

MATTHIAS BROCK, OF BOSTON, MASSACHUSETTS, ASSIGNOR, BY MESNE ASSIGNMENTS, TO UNITED SHOE MACHINERY CORPORATION, OF PATERSON, NEW JERSEY A CORPORATION OF NEW JERSEY.

LASTING HEEL-BAND AND METHOD OF MAKING THE SAME.

1,257,670.

Specification of Letters Patent. Patented Feb. 26, 1918.

Application filed June 3, 1915. Serial No. 31,907.

To all whom it may concern:

Be it known that I, MATTHIAS BROCK, a citizen of the United States, residing at Boston, in the county of Suffolk and State of 5 Massachusetts, have invented certain Improvements in Lasting Heel-Bands and Methods of Making the Same, of which the following description, in connection with the accompanying drawings, is a specification, 10 like reference characters on the drawings indicating like parts in the several figures.

This invention relates to end embracing bands for shoes. These bands are employed in lasting and other shoe making operations. 15 One extensive use of end embracing bands is to clamp the upper materials closely against the side faces of the heel portion, and sometimes of the toe portion, of a last for producing in the upper materials of the shoe 20 the shape of the last and holding them in that shape while the edge portions of the upper materials are molded over the edge and upon the margin of the bottom of the shoe and fastened to the innersole. It is by 25 thus molding the upper to the side faces of the last and then to the edge and margin of the shoe bottom and fastening the upper to the innersole while still held to the side faces of the last that the most perfect 30 production of the shape of the last is obtained in the shoe.

For some uses there are desired bands having characteristics not possessed by bands heretofore provided. For example, a band 35 for satisfactory use on white uppers and the various colored uppers must be capable of performing its function without discoloring or in any way leaving a mark on the uppers; also, under some conditions the best 40 upper shaping results are obtained if the toe band of a lasting machine is sufficiently pliable so that it can be held by its operating mechanism substantially in a V-shape while open and can be forced by the insertion of the shoe into the U-shape required to fit the 45 toes of most shoes. Furthermore, it is desirable when operating upon white and delicate colored goods to use the same band exclusively for the same color of goods and 50 this necessitates an equipment of several bands for each machine and renders it important to use an inexpensive band.

These practical conditions in the trade

led me to experiment with other materials than those commonly used and these experiments have resulted in the discovery that by a treatment which I have devised an end embracing band having the highly desirable characteristics above mentioned, including inexpensiveness together with durability, 55 could be produced from fibrous materials, including particularly felt. The present invention consists in a novel method of treating material such as felt and in an article such as an end embracing band so produced. 60 I will now proceed, with the aid of the accompanying drawings, to explain fully this novel method and an end embracing band which may be produced by this method, and will then particularly point out the invention 65 in the annexed claims.

In the drawings:

Figure 1 shows a strip or block of felt of proper length and width to be used as a blank for making an end embracing band. 75

Fig. 2 illustrates the operation of removing surplus material from the inner side of the blank to assist in fitting the inner face to the vertical curvature of the side of a last.

Fig. 3 shows a backing sheet of tough 80 paper, canvas or leather to be applied to the outer face of the felt to resist wear and exclude moisture from said outer face.

Fig. 4 shows the outer portion of the blank after having been treated with shellac which 85 has penetrated only partially through the body of the blank, and after the backing strip has been applied to the shellac-coated surface.

Fig. 5 illustrates the step of subjecting 90 the shellacked blank and backing shown in Fig. 4 to compression to cause the shellac to penetrate toward but not to the inner face to condense the felt, particularly the portion which is wet with shellac, to obtain intimate adhesion of the backing, and to shape the blank into the required form for a toe or heel band.

Fig. 6 is a perspective view of the band produced, the band being mounted upon its 100 carrier chain ready for use.

Fig. 7 is a section of the same in use.

As the invention is shown in the drawings for illustrative purposes, a blank 1 of felt is selected which has the length, breadth and 105 thickness to produce the desired size of end

embracing band, for example a toe embracing band. This blank is preferably first shaped on that side which is to be the inside of the band to fit the vertical curvature of the portion of the shoe or last which it is to embrace. This shaping is advantageously performed by cutting away the felt stock, as illustrated in Fig. 2, to form a depression or recess as indicated in Figs. 6 and 7. This cutting may be done with a rotary abrading tool 2. I then apply to the side of the blank which is opposite to the cut away side a liquid material such as shellac which can be made to penetrate the felt for a substantial portion of the thickness of the blank, as indicated in Fig. 4, and which when it dries will harden the portion of the felt which it penetrates. To the coated surface of the blank I preferably, although not necessarily apply a backing of sheet material 3, Fig. 3, of tough paper, fabric or leather adapted to resist the wear to which the back face of a band is subjected from contact with its carrier or support. The backing strip 3 may well be coated with glue or shellac before it is applied to the blank. The blank, with the backing secured to it by the wet shellac, is now bent lengthwise and molded to the shape which it is desired that the end embracing band shall possess. This may be done in molds 4, 4, 5, as indicated in Fig. 5. Preferably the band will be subjected to very substantial molding pressure and the shellac or other stiffening material thereby forced well into but not fully through the thickness of the band. The molds may advantageously be formed to deflect inwardly the upper edge of the blank, as at 6, Figs. 6 and 7, to adapt the band to the form of band carrier 7 with which I prefer to employ it. The shellac or other hardening material is allowed to dry while the blank is bent into the form of an end embracing band, and the band is then ready for use, as indicated in Figs. 6 and 7.

Having explained the nature of this invention and described how it may be employed, I claim as new and desire to secure by Letters Patent of the United States:—

50. 1. That improvement in methods of making shoe end embracing bands having relatively soft inner faces and relatively hard outer portions which consists in cutting away one face of a blank of felt to form the inner face of the band, applying to the reverse face of the blank enough shellac in liquid form to soak into the felt for a substantial distance, applying a backing of wear-resisting sheet material to the shellac-coated outer face of the blank, bending the blank and backing sheet together into the form of an end embracing band, producing penetration of the felt by the shellac partially through the band by pressure applied through the backing sheet, and allowing the

shellac to set or dry, all while the inner face of the band is maintained free from the felt-hardening effect of the shellac.

2. That improvement in methods of making shoe end embracing bands having relatively soft inner faces and relatively hard outer portions which consists in applying to that face of a blank of fibrous material which is to form the outside face of the band enough liquid stiffening material to soak into the blank for a substantial distance, applying a backing of wear-resisting sheet material to the coated outer face of the blank, bending the blank and backing sheet together into the form of an end embracing band, producing penetration of the blank by the stiffening material partially through the band by pressure applied through the backing sheet, and allowing the stiffening material to set or dry, all while the inner face of the band is maintained substantially free from the felt-hardening effect of the shellac.

3. That improvement in methods of making end embracing bands for shoes which consists in cutting away material from that face of a blank of felt which is to form the inner shoe engaging face of the band and thereby contouring said face to receive a portion of the shoe end; applying to the reverse face of the blank a material which can be made to penetrate the felt for a portion of the thickness of the blank and which, when dried, will harden the portion of the felt which it penetrates; applying a backing of sheet material to said outer face of the blank; bending the blank into a band formed to embrace a shoe end; and applying compression in a way tending to effect penetration of the felt by the hardening material and adhesion of the backing to the body of the band.

4. That improvement in methods of making end embracing bands for shoes which consists in producing in that face of a blank of felt which is to form the inner face of the band a depression or recess to fit a portion of the shoe, applying to the outer face of the blank a fluid material which is adapted to penetrate the felt and harden the outer portion of the band without extending the hardening effect to the inner shoe-engaging face of the band, bending the blank longitudinally into the shape of an end embracing band, and drying the hardening material while the band is so bent.

5. That improvement in methods of making end embracing bands for shoes which consists in coating a blank of felt on one side with stiffening material, attaching a backing strip of wear-resisting sheet material to the coated surface by adhesion, shaping the blank and attached backing strip into the form of an end embracing band while the stiffening material is yet soft, and allowing

the stiffening material to harden while the band is in the end embracing form and while maintaining the inner shoe-engaging face of the felt band in soft condition so that it can 5 adapt itself to the surface of the shoe upper during use in a lasting operation.

6. That improvement in methods of making end embracing bands for shoes which consists in wetting one side of a strip of felt 10 with shellac, subjecting the strip to such compression in the direction of the thickness of the strip as to shape the felt to the form of an end embracing band and to distribute the shellac partially but not entirely through 15 the thickness of the felt, and hardening the portion of the felt which is at and adjacent to the outer face of the band relatively to the portion at the inner face of the band without destroying the flexibility of the 20 band by allowing the shellac to dry or set while the band is in approximately the shape to which it has been molded.

7. That improvement in methods of making end embracing bands for shoes which 25 consists in applying to one side face of a strip of felt a material adapted to penetrate the felt and to harden its surface, subjecting the strip of felt so treated to compression to cause the applied material partially to 30 penetrate the felt without destroying its flexibility, shaping the felt to a contour to embrace the end portion of a last, and drying it while it remains in the shape given to it in the shaping operation.

35 8. A flexible end embracing band comprising a body portion of homogeneous felt

having a soft inner face and having felt hardening material extending from the outer face of the band partially through its thickness.

9. An end embracing band comprising a 40 molded U-shaped body portion of felt cut away on its inner face at the bend to the vertical curvature of the side face of a last end and having the material of its outer face 45 stiffened and hardened, substantially as described.

10. An end embracing band comprising a 45 body portion of felt permeated and stiffened for a substantial distance inwardly from its 50 outer face by shellac and molded into a U-shaped form, and a backing of wear-resisting material secured to said outer face by the shellac.

11. As an article of manufacture, a flexible 55 member for engaging a shoe upper to conform it to its last composed of felt having a relatively soft shoe engaging inner face and an outer pressure receiving face permeated and hardened by a stiffening 60 agent.

12. As an article of manufacture, a flexible 65 substantially U-shaped felt band for embracing the end of a shoe having a relatively soft shoe-engaging inner face and an outer pressure receiving face permeated and hardened by shellac distributed partially, but not entirely, through the thickness of the felt.

In testimony whereof I have signed my name to this specification.

MATTHIAS BROCK.
